UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

SPEED-CONTROL GOVERNOR.

Application filed April 8, 1925. Serial No. 21,533.

To all whom it may concern:

Be it known that I, CLYDE C. FARMER, a citizen of the United States, residing at Pittsburgh, in the county of Allegheny and 5 State of Pennsylvania, have invented new and useful Improvements in Speed-Control Governors, of which the following is a specification.

This invention relates to train speed control apparatus and more particularly to a 10 governor device therefor.

On some railroads, the locomotives are from time to time alternately used in passenger and freight service, and the operating 15 rules of the railroad may prescribe different speed limits, to be maintained in the different classes of service. For this reason it is desirable, where speed control apparatus is applied to the locomotives, to have 20 means for regulating said apparatus, so that different speed limits may be maintained, according to the class of service in which the locomotives are used.

The principal object of my invention is 25 to provide improved means for adjusting speed control apparatus so that different speed limits may be imposed on the train according to the class of service in which the locomotive is being used.

30 In the accompanying drawing; Fig. 1 is a sectional view of a speed control governor with my invention embodied therein; Fig. 2 a section taken on the line 2—2 of Fig. 1; Fig. 3 a section taken on the line 3—3 of 35 Fig. 2; and Fig. 4 a section taken on line 4—4 of Fig. 2.

As shown in the drawing, the device may comprise a casing 1 having a partition 2, in which is provided a bearing for one end of 40 a main rotating member 3, the opposite end of which carries a pinion 4, said pinion being operatively connected to the locomotive axle.

Pivottally mounted on the member 3 are 45 the usual weighted governor arms 5 having rollers 6, which are adapted to engage a sleeve 7, said sleeve being mounted on a shaft 9, which has a bearing at one end in the casing 1 and at the other end in the rotating 50 member 3. Interposed between the sleeve 7 and a flanged portion of the rotating member 3 is a spring 8, which opposes movement of said sleeve toward the right.

The shaft 9 is provided with a crosshead

10 in which are disposed valve tappets 11 55 and 11^A, of which there may be any number, two only being shown for the purpose of illustration. The tappet 11^A projects at a greater distance from the right hand face of the crosshead 10 than does the tappet 60 11, and said tappets are alternately adapted, according to the rotative position of the crosshead 10 and upon movement thereof to the right or to the left, to engage the stem of a speed control valve 12 disposed in the 65 casing 1.

Attached to the casing 1 is a bracket portion 24 in which is mounted a shaft 13. Secured to the protruding end of the shaft 13 is a handle 14 having a spring pressed 70 latch 15, which is adapted in one position of said handle, to register with a hole 16 in a latch plate 17 secured to the bracket portion and in another position of the handle to engage a hole 18 in said latch plate. 75

Mounted on the shaft 13 is a sleeve 19 which has downwardly extending arms 20 and is provided with a squared opening adapted to receive a correspondingly shaped portion of the shaft 13, so that a rotation 80 of the shaft 13 will also rotate the sleeve 19. Mounted in the arms 20 is a pin 21 carrying an elongated square block 22, which is adapted to engage, with a sliding fit, a correspondingly shaped recess 23 in the cross- 85 head 10 so as to thereby furnish a guide for and permit a lateral movement of said crosshead.

If the locomotive is to be used in passenger service, the handle 14 is placed in the position shown in the drawing, so that spring pressed latch 15 registers with the hole 16 in the latch plate. The cross head 10 is now in a position so that valve tappet 11 is in line with the stem of valve 12, and as the 95 member 3 is rotated by the operative connection to the locomotive axle, the arms 5 will act through the sleeve 7 to move the cross head 10 to the right and cause tappet 11 to engage the stem of the valve 12. 100

If, however, the locomotive is to be used in freight service, the handle 14 is moved, with a consequent rotation of the shaft 13, to a position in which the spring pressed latch 15 will register with a hole 18 in the latch plate 17. The rotation of the shaft 13, as hereinbefore described, rotates the sleeve 19, and consequently the crosshead 10, to a 105

position so that the other projecting tappet 11^a will be in alinement with the stem of valve 12.

Now as the member 3 is rotated by the operative connection to the locomotive axle, a lesser movement of the crosshead 10 to the right will cause the tappet 11^a to engage the stem of the valve 12 so as to thereby unseat said valve.

Having now described my invention, what I claim as new and desire to secure by Letters Patent, is:—

1. The combination with a speed governor provided with a longitudinally movable and rotatable crosshead, of a valve, a plurality of tappets carried by said crosshead and each adapted to engage said valve at different rotative positions of the crosshead upon longitudinal movement of the crosshead, and means for rotating said crosshead.

2. The combination with a speed governor provided with a longitudinally movable and rotatable crosshead, of a tappet valve, a plurality of tappets carried by said crosshead, each tappet being adapted to aline with said valve at different rotative positions of the crosshead for operating said valve upon longitudinal movement of the crosshead, and manually operated means for rotating said crosshead.

3. The combination with a speed governor having a longitudinally movable crosshead, of means for rotating said crosshead comprising a rotatable member disposed in a recess formed in the crosshead and adapted to permit longitudinal movement of the crosshead and means for rotating said member.

4. The combination with a speed governor provided with a longitudinally movable crosshead and having an open ended slot, of a rotatable block mounted in said slot and adapted to permit longitudinal movement of said crosshead, and manually rotatable means connected to said block for rotating said block and thereby said crosshead.

5. The combination with a speed governor provided with a longitudinally movable crosshead and having an open ended slot, of a rotatable block mounted in said slot and adapted to permit longitudinal movement of said crosshead, manually operable means for rotating said block and thereby said crosshead, and means for locking said manually operable means in different rotative positions.

In testimony whereof I have hereunto set my hand.

CLYDE C. FARMER.
